United States Patent Office

Des. 230,394

Patented Feb. 19, 1974

230,394

BUS

Humberto Arroyo-Lopez, Nort 87, 459,
Mexico 16, D.F., Mexico City, Mexico

Filed Aug. 17, 1972, Ser. No. 281,305

Term of patent 14 years

Int. Cl. D12—08

U.S. Cl. D12—84

FIG. 1

FIG. 2

FIG. 1 is a perspective view showing the front and one side of a bus embodying my new design.

FIG. 2 is a perspective view showing the back and the other side of a bus embodying my new design.

The undisclosed top is substantially plain and unornamented and follows the contour of the roof line shown in FIGS. 1 and 2.

I claim:

The ornamental design for a bus, as shown and described.
